MASSAGING ROLLER

John Waldeck, 2764 Faber Ave., Cincinnati, Ohio 45211

Filed Dec. 8, 1965, Ser. No. 119

Term of patent 14 years

(Cl. D83—1)

Fig.1

Fig.2

Fig.3

Fig.4

FIGURE 1 is a side elevation of a massaging roller showing my new design with the handle members omitted for convenience of illustration.

FIGURE 2 is a top plan view thereof.

FIGURE 3 is an end elevation thereof.

FIGURE 4 is a perspective view with the inclusion of the handle members.

The side and end of the massaging roller not shown, are the same as the side and end shown.

I claim:

The ornamental design for a massaging roller, substantially as shown and described.
